UNITED STATES PATENT OFFICE.

THEODORE F. SCHIRMER, OF DAYTON, OHIO, ASSIGNOR TO THE STANDARD REGISTER COMPANY, OF DAYTON, OHIO, A CORPORATION OF OHIO.

AUTOGRAPHIC REGISTER.

1,277,489.

Specification of Letters Patent. Patented Sept. 3, 1918.

Application filed September 21, 1914. Serial No. 862,653.

To all whom it may concern:

Be it known that I, THEODORE F. SCHIRMER, a citizen of the United States, and a resident of the city of Dayton, in the county 5 of Montgomery and State of Ohio, have invented certain new and useful Improvements in Autographic Registers, of which the following is a full, clear, and exact description, reference being had to the accompanying 10 drawings, forming part of this specification.

The kind of register to which my invention has special application is the crank operated register having a record strip which remains within the machine, and the invention 15 has relation to the arrangements for mounting the record roll to receive the record strip, and means for applying friction to the feeding rolls and relieving the same.

The object of my invention is to provide a 20 record roll which is locked in position until the machine is open and tension rolls which can both be lifted by a finger pull, permitting the record strip to be drawn over the rolls, torn off, and remounted on the record 25 roll without disturbing the check strips. In the register shown, the check strips are held in place during this operation by the perforations thereon, but any other desired means could be used for this purpose without de- 30 parting from the spirit of my invention.

The manner in which my object is accomplished will be hereinafter specifically pointed out and claimed and the principal advantages noted.

35 In the drawings,

Figure 1 is a side elevation of the register with the casing broken away to show the record and check rolls.

Fig. 2 is a top plan view of the register 40 with the top portion of the casing removed.

Fig. 3 is a vertical longitudinal section of the machine, taken just inside of the cam lever for shifting the tension rolls.

Fig. 4 is a perspective view of the mounting and locking means for the record strip record roll.

Fig. 5 is a diagrammatic view showing the course of the three strips used.

Fig. 6 is a detail of the top friction roll 50 mounting.

Figs. 7 and 8 are details showing the friction device for the main feed roll.

The machine has a casing having side

walls 1, 1, and a writing tablet 2, over which the paper strips pass, a cover plate 55 2^a and it has also a door 3 hinged at 4 to the base of the casing. A sliding top 5 is secured in a groove 5^a formed in the side walls, and ears 6, 6, on this sliding top engage over tongues 7, 7, on the tablet top. 60

The casing above described is no more than an ordinary form of casing for autographic registers of the recording type, and it will be understood that the door and sliding top cover that part of the compartment 65 where the record roll is kept and where it is desired to have access to the machine interior to remove this roll. A lock 8 is preferably used to hold the door closed to lock the register, thereby allowing the proprietor 70 who holds the key to have sole access to the storage roll.

Mounted on spindles 9, 9, 9, in the side walls 1, 1, are the rolls 10, 10, for the check and duplicate check strips A and B, and 75 the roll 11 for the record strip C. These strips are brought up and passed over rollers 12. They are then drawn forward over the writing tablet 2 and passed between the main feed roll 13 and the friction roll 14. 80 The strips A and B are then brought out and torn off.

For a further description of the roller 14 which is of familiar use in the art, see patent to Schirmer, No. 940,481, Nov. 16, 1909, the 85 roller 22, as shown in Fig. 6.

The record strip C, however, is drawn around the feed roll, underneath the additional tension roll 15 and then is wound over the record roll 16, mounted between 90 the sides of the register.

The mounting of this record roll is as follows (Fig. 4): a spindle 17 is provided having a knurled head 18. This spindle finds bearings in the sides 1, 1, of the register and passes through the record roll. A circumferential groove 19 is formed in the spindle at the point that lies normally just inside the casing, and mounted on the inside 95 of the casing is a small spring finger 20 that is normally held in the groove. This finger lies entirely inside the casing and must be raised out of the way before the spindle can be withdrawn.

It is easy to appreciate that the device 105 simply but adequately prevents the spindle

from being withdrawn accidentally or deliberately without having access to the inside of the casing. It holds the spindle securely in place and still allows it to be drawn out when the box is unlocked.

The tension roller 14 is mounted on a spindle 21 which rides in a slot 22 on each side of a box 23 which forms part of the tablet top (Fig. 6). This box is positioned so that it brings the roll directly over the feed roller, and spring pressed plungers 24 at each side, mounted in sockets 25 in the box 23, press down on the spindle 21 to supply the tension. The tension roller is thus normally held against the feed roller, but is capable of being pressed up away therefrom.

The record strip tension roller 15 is mounted similarly to the roller 14, but in the side of the casing. Slots 26, 26, in the sides 1 receive the spindle 27 of this roller 15, and spring plungers 28, 28, at each side are mounted in small boxes 29 so as to press against the spindle 27. This pressure keeps the roller tight against the feed roller, but as in the instance of the first roller it can be pushed away from this position against the spring pressure to relieve the tension.

A means is provided whereby a series of interacting cams move the tension rollers out of contact position (Fig. 3). A pivoted lever 30, on the casing 1, having a finger hold 31, has a cam end 32 in contact with the arm of a bell crank 33. The other arm of the bell crank lies against the spindle 27 of the tension roller 15. When the lever 30 is pulled up at the end 31, this will press the bell crank upper arm against the spindle of the roller 15, throwing it out of the way (see dotted lines Fig. 3 for this position). The bell crank 33 is mounted on a spindle 33^b that is journaled in the sides of the casing, and this spindle has a cam finger 33^a (Fig. 2) at the other side of the casing located so as to contact with the spindle 27 at its other end, in the same manner as the bell crank arm above referred to so that the spindle 27 is shifted by pressing at both ends.

When the lever 30 is raised, it will remain in that position owing to the spring pressure against the bell crank and the shape of the cam end 32.

The upper bell crank arm lies against the foot 34 of a cam 35, pivoted to the casing. The cam 35 presses against the periphery of the tension roller 14, and when the bell crank is swung this cam 35 is raised up thereby pushing said roller 14 out of tension position.

The operation of the register by means of the crank 36 is as follows. The crank is keyed on the spindle 37 of the feed roller 13. Mounted on the feed roller at each end is a disk 38^a provided with a series of teeth 38, which coöperate with the perforations 39

on the check strips A and B to hold the strips firmly and in an unchanging relation to each other.

The spindle has also a cam 40 at each end located so as to raise the tension roll slightly 70 while the feed roll is being turned, and a pin 41 on this cam engages a spring pawl 42 to hold the spindle against backward rotation.

A gear 43 on the spindle meshes with a gear 44 on the casing, which in turn meshes 75 with a gear (not shown) fast on the record roll 16.

It will be understood that this crank operating mechanism is not claimed as new in this case. The means for supplying carbon 80 paper to this register is not shown either. It will be understood that a piece of such paper is passed between the strips on the tablet top, so that writing on the top check strip will make an autographic copy on the 85 duplicated check strip and the recording strip.

In removing the record roll, the door is unlocked and swung back, and the machine is open as far as necessary. The lever 30 is 90 raised to relieve all tension, the finger 20 swung away and the spindle 18 withdrawn. The roll is then removed from the machine, and the strip torn off so as to get the most recent record.

In returning the roll, the strip is pulled out as far as is necessary for securing it to the roll. This can be done without altering the position of the check strips, because the record is not perforated and does not engage the pins on the feed roll whereas the check strips are perforated and held by the pins. As was said before, however, some other means of holding the check strips without retaining the record strip, would 105 serve the same purpose as the perforations and pins as far as this invention is concerned.

The feature of a tension roller located at the side of the feed roller to keep taut a recording strip is a valuable one in this device. The record strip is held taut and absolutely non-binding without any lateral strain on the web of paper.

Inasmuch as the record roll is driven by 115 the feed roll, some arrangement must be provided to allow slippage of the one roll with reference to the other as the paper is wound on the record roll.

Mounted on the enlargement 45 of the spindle of the feed roll 13 and abutting against the cam plate 40 on the end of the feed roll opposite the crank is a fiber washer 46, and against this washer the side face of the gear 43 bears, which gear is loosely 120 mounted on the spindle portion 45. Then another fiber washer 48 is placed on the spindle abutting against the opposite face of the gear 43, and pressure is applied to the gear and washers by the annular spring 125 130

plate 49, provided with a plurality of fingers 50. The spring plate is cup shaped, and the ends of the fingers bear upon the washer while a nut 51 is mounted on the screw-threaded end of the spindle to obtain the proper tension for the spring plate. In this way the gear 43 can slip under the spring tension as the diameter of the web changes on the record roll.

10 Reference to specific mechanical expedients or the adoption of any certain kind of register, where not specifically noted, is not done with the intent of limiting the claims that follow to any specific one out of the 15 field of equivalents.

Having thus described my invention, what I claim as new and desire to secure by Letters Patent, is:

1. In an autographic register, a main roll, 20 toothed feeding means spaced apart on said roll to receive and feed strips of paper perforated marginally, said space between the feeding means adapted to receive a narrow record strip, a record strip receiving roll 25 adapted to be rotated to take up the record strip, a tension roll located against the side of the main roll, to engage the record strip against the roll in its path therefrom to the receiving roll and a tension roll located 30 against the top of the main roll to engage and hold taut the record strip at the termination of each feeding operation.

2. In an autographic register, a main roll, 35 toothed feeding means spaced apart on said roll to receive and feed strips of paper perforated marginally, said space between the feeding means adapted to receive a narrow record strip, a record strip receiving roll adapted to be rotated to take up the record 40 strip, and a tension roll located against the side of the main roll, to engage the record strip against the roll in its path therefrom to the receiving roll, said main roll having likewise an additional tension roll positioned 45 to frictionally hold all strips against the main roll.

3. In an autographic register, a main feed 50 roll adapted for underlying a plurality of check strips and a record strip, a sprocket feed for the check strips on the main roll, a tension roll located so as to press directly against the top of said roll against all of

the strips, an additional tension roll located so as to press against the side of the feed roll, a record roll to receive the record strip 55 after it has passed under both tension rolls, and means for raising both tension rolls simultaneously to remove their tension.

4. In an autographic register, a main feed roll adapted to receive both a record strip 60 and a check strip, a feed for the strips on the main roll, a tension roll to hold said strips against said feed roll said roll serving to hold taut the record strip at the termination of the feed, with the record strip passed 65 part way around the feed roll, an additional tension roll to hold said record strip against the feed roll at the point where it is drawn away for storage, and means for raising both tension rolls simultaneously to remove their 70 tension.

5. In an autographic register, in combination, an actuated and an idler feeding roller for simultaneously feeding a check strip and a record strip, the actuated roller comprising in part means for holding the check strip from moving until the actuated feeding roller is operated, a tension roller for the record strip, means for movably mounting the same against the actuated feeding roller, 80 and means for simultaneously moving the tension roller and the idler roller away from the actuated feeding roller, so that the record strip can be pulled out without disturbing the check strip. 85

6. In an autographic register, in combination, an actuated and an idler feeding roller for simultaneously feeding a check strip and a record strip, the actuated roller comprising in part means for holding the check 90 strip from moving until the actuated feeding roller is operated, a tension roller for the record strip, means for movably mounting the same against the actuated feeding roller, and a set of interacting cams for simultaneously moving the tension roller and the idler roller away from the actuated feeding roller, so that the record strip can be pulled out without disturbing the check strip. 95
